UNITED STATES PATENT OFFICE.

LOUIS E. LADD, OF PROVIDENCE, RHODE ISLAND, ASSIGNOR TO POTTER & BUFFINTON COMPANY, A CORPORATION OF RHODE ISLAND.

SETTING.

1,114,370.

Specification of Letters Patent.

Patented Oct. 20, 1914.

Application filed July 2, 1914. Serial No. 348,692.

To all whom it may concern:

Be it known that I, LOUIS E. LADD, a citizen of the United States, residing at Providence, in the county of Providence and 5 State of Rhode Island, have invented certain new and useful Improvements in Settings, of which the following is a specification.

My invention relates to gem settings of the two-piece type, that is to say, settings comprising a body portion located upon a base portion. It has heretofore been attempted to assemble these settings by locating the two members relatively to each other 10 by the eye prior to their engagement. The small size of the parts and their irregularity of contour have rendered it practically impossible to arrange them concentrically. To the end of overcoming this 15 difficulty, and of attaining the desired result in a cheap and ornamental structure, my invention consists in such parts and combinations of parts as fall within the scope of the appended claims.

20 In the accompanying drawings which form a part of this specification, Figures 1 and 2, are plan and side elevations respectively of the base member, Figs. 3 and 4, similar views respectively of the blank bent into 25 final position, Fig. 5, a plan of the complete setting, and Fig. 6, a section of the same on line α , α , of Fig. 5.

Like reference characters indicate like parts throughout the views.

30 In constructing my setting a blank is cut and formed by suitable tools from thin metal. It comprises a substantially circular body a provided with openings to admit light to a gem. These openings in the present instance consist of a central circular opening a' , and radial openings a^2 , producing a resultant annular base a^3 , and upwardly inclined radial arms a^4 connected at their outer ends by a substantially circular 35 scalloped border a^5 . Integral with this border are radial arms B , as shown in Figs. 1 and 2. The arms B are next folded over upwardly, inwardly, and downwardly, forming

ing loops b , the free end portions b' of the arms are downwardly and inwardly inclined from the outer portions of the body 50 A to the inner surface of the portion a^3 thereof with which they contact thus forming a series of substantially conical bearing surfaces as will be later seen. The setting 55 member C comprises in the present instance a cup having a bottom c provided with a central opening to admit the light and with supporting prongs c' rising from the body adapted to embrace a gem. In assembling 60 these parts the operator manually places the member C in the member B concentrically with the latter, by resting the bottom c upon the inclined portions b' which center the setting automatically. Then the solder 65 may be applied to the parts at the point d .

What I claim is,—

1. A setting consisting of a base member in a single integral element comprising a substantially circular body with openings, upwardly 70 then inwardly and then downwardly inclined radial arms having a scalloped border between said arms, and a cup seated upon the arms and provided with prongs to support a gem. 75

2. In a setting, a base provided with a body and a central opening and with upwardly then inwardly and then downwardly inclined arms converging from the periphery of the body to the base around said opening and a cup seated upon said downwardly and inwardly inclined arms and having prongs. 80

3. In a setting, the combination of a base, a body upon the base, arms upon the body 85 extending first upwardly, then inwardly and then downwardly toward the center of the base, a cup seated upon the arms, and prongs upon the cup.

In testimony whereof I have affixed my 90 signature in presence of two witnesses.

LOUIS E. LADD.

Witnesses:

EDW. H. ZERGLER,
HORATIO E. BELLOWES.
